US00D914192S

(12) **United States Design Patent** (10) Patent No.: **US D914,192 S**
(45) Date of Patent: **** Mar. 23, 2021**

(54) **APPARATUS FOR MEDICAL OR
LABORATORY DIAGNOSIS**

(71) Applicant: **Calmark Sweden AB**, Karlstad (SE)

(72) Inventors: **Michael Lundh**, Lund (SE); **Anna Söderlund**, Årsta (SE); **Tania Correia**, Stockholm (SE); **Catarina Moreira Pinho**, Bromma (SE); **Johan Svahn**, Lärbro (SE)

(73) Assignee: **Calmark Sweden AB**, Karlstad (SE)

(**) Term: **15 Years**

(21) Appl. No.: **35/508,180**

(22) Filed: **Nov. 1, 2019**

(80) **Hague Agreement Data**

Int. Filing Date: **Nov. 1, 2019**

Int. Reg. No.: **DM/204688**

Int. Reg. Date: **Nov. 1, 2019**

Int. Reg. Pub. Date: **Dec. 20, 2019**

(51) **LOC (13) Cl. .....** 24-01

(52) **U.S. Cl.**

USPC **D24/107**

(57) **CLAIM**

The ornamental design for an apparatus for medical or laboratory diagnosis, as shown and described.

DESCRIPTION

1. Apparatus for medical or laboratory diagnosis

1.1 : Perspective

1.2 : Front

1.3 : Top

1.4 : Right

1.5 : Bottom

1.6 : Left

1.7 : Back

1 Claim, 7 Drawing Sheets
